UNITED STATES PATENT OFFICE.

JOHN DONNELLY, OF BRANFORD, CONNECTICUT.

TOBACCO-PIPE.

1,115,412.

Patented Oct. 27, 1914.

Application filed June 8, 1914. Serial No. 843,712.

To all whom it may concern:

Be it known that I, JOHN DONNELLY, a citizen of the United States, residing at Branford, in the county of New Haven and State of Connecticut, have invented a new and useful Improvement in Tobacco-Pipes; and I do hereby declare the following, when taken in connection with the accompanying drawings and the characters of reference marked thereon, to be a full, clear, and exact description of the same, and which said drawings constitute part of this application, and represent, in—

Figure 1 a side view of a tobacco pipe constructed in accordance with my invention. Fig. 2 a top or plan view of the bowl portion of a pipe showing my improved cover applied thereto, and in broken lines indicating the open position. Fig. 3 a perspective view of the cover detached. Fig. 4 a side view of a modified form of cover applied to the pipe. Fig. 5 a perspective view thereof.

This invention relates to an improvement in tobacco pipes, and particularly to covers therefor, the object of the invention being to provide a cover which will firmly remain in place in either its open or closed position which may be readily opened by a finger of the hand holding the pipe so that the pipe may be opened for filling and tamping with one hand in case the other hand is engaged.

In carrying out my invention I employ a pipe 2 of substantially usual construction having the usual bowl 3 which, as shown in Fig. 1 of the drawings, has a flat top 4 and a flat bottom 5. The cover as shown in Figs. 1, 2 and 3 of the drawings comprises a head 6 corresponding in dimensions to the top of the bowl of the pipe and provided with perforations 7 more or less in number. The cover also comprises a base 8 which in the form of the pipe shown in Fig. 1, will be of disk shape corresponding in dimensions to the bottom of the pipe, and the head 6 and bottom 8 are connected by a strap 9 preferably formed integral with them. The head and bottom are respectively pivotally connected with the bowl by screws or pins 10 and 11. These are preferably arranged in line with each other and slightly to one side of the longitudinal center of the bowl, so that the cover can only be turned in one direction. As it is turned into the closed position the strap 9 will bind

against the front wall of the bowl and owing to the point of pivotal connection this strap will not pass beyond the center of the bowl, and by crowding against the wall of the bowl forms a lock to hold the cover in place. This strap, moreover, forms a finger-piece by which the cover may be swung into or out of place by one of the fingers of the hand holding the bowl, and as this strap extends toward the bottom of the bowl the cover may be moved from a point below the upper end of the bowl or of the top part of the cover which naturally is hot when in use. It is evident without illustration, that the cover might be secured to the bowl in a central longitudinal line, but preferably for the reason above set forth, the pivotal point will be slightly to one side of that.

In case the pipe is not provided with a flat bottom as shown in Fig. 1 of the drawings but is rounded as shown in Fig. 4 of the drawings, the base 8 instead of being a disk, will simply be in the form of an arm 12 extending inward from the lower end of the strap 9; or in other words the strap 9 will be extended in a curved line corresponding to the curvature of the bowl of the pipe so that its end may be brought into line 35 with the inner edge of the cover 6; and it is also evident as indicated in broken lines in Fig. 3 that the base for a flat bottomed pipe might be in the form of an arm substantially like that shown in Fig. 5 of the drawings. 90 I therefore do not wish to be understood as limiting my invention to the particular form of cover. This construction permits the cover to be swung entirely away from the opening in the bowl of the pipe as shown 95 in Fig. 2 of the drawings, so that the pipe may be filled or emptied without obstruction. These covers are readily applied to pipes and perform the function of usual forms of pipe covers. Preferably the surface of the cover around the perforations will be roughened to provide a surface for striking matches but it is evident that the roughened surface might be formed on the base.

I claim:—

1. In a tobacco pipe, the combination with the bowl thereof, of a cover pivotally connected with the upper end of the bowl, a strap extending downward and beneath the bowl and pivotally connected thereto.
2. In a tobacco pipe, the combination

with the bowl thereof, of a cover pivotally connected with the upper end of the bowl, a strap extending downward and beneath the bowl and pivotally connected thereto, a portion of the cover formed with a roughened surface.

In testimony whereof, I have signed this

specification in the presence of two subscribing witnesses.

JOHN DONNELLY.
